UNITED STATES PATENT OFFICE.

HERMAN G. HORNING, OF NEW YORK, N. Y.

SPARK-PLUG.

1,272,954.

Specification of Letters Patent. Patented July 16, 1918.

Application filed March 6, 1917. Serial No. 152,749.

To all whom it may concern:

Be it known that I, HERMAN G. HORNING, a citizen of the United States, and a resident of the city of New York, borough of Manhattan, in the county and State of New York, have invented a new and Improved Spark-Plug, of which the following is a full, clear, and exact description.

The invention relates to spark plugs having a plurality of spark gaps, and its object is to provide a new and improved spark plug arranged to permit of conveniently adjusting the sparking elements to provide a larger or a shorter spark gap to suit existing conditions, and to reduce to a minimum the clogging up of the sparking elements by carbon deposits and other extraneous matter.

In order to accomplish the desired result, use is made of two conductors each provided with a plurality of sparking members arranged in a circle and spaced equal distances apart, the sparking members of the conductors being arranged in alternate relation to form spark gaps between adjacent sparking members, at least, one of the said conductors being rotatable relative to the other to adjust the sparking members nearer to or farther from the sparking members of the other conductor to correspondingly reduce or increase the spark gaps.

A practical embodiment of the invention is represented in the accompanying drawings forming a part of this specification, in which similar characters of reference indicate corresponding parts in all the views.

Figure 1 is a side elevation of the spark plug;

Fig. 2 is an enlarged central section of the same;

Figs. 3 and 4 are side elevations of the sparking members;

Fig. 5 is a sectional side elevation of the inner portion of a spark plug provided with a modified form of insulation;

Fig. 6 is a central section of another modified form of the spark plug;

Fig. 7 is a side elevation of the inner portion of another modified form of the spark plug; and

Fig. 8 is an inverted form of the same.

The body 10 of the spark plug is provided with the usual threaded portion 11 adapted to screw into the usual tapped hole of the cylinder of the engine, and the upper end of the body 10 is in the form of a polygonal head 12 adapted to be engaged by a wrench or other tool for screwing the spark plug in position on the cylinder or unscrewing it therefrom. The body 10 is provided with two concentric bores 13 and 14 into which fit correspondingly shaped inner and intermediate portions 15 and 16 of a core 17 made of porcelain or a similar insulating material.

The core 17 is provided with a central aperture 18 through which extends a conductor 19 in the form of a rod provided at its inner end with a head 20. A sparking member 21 is held on the inner end of the conductor 19 and rests on the head 20, and the peripheral edge of the sparking member 21 is provided with angular members 22, preferably triangular in shape, and spaced equal distances apart, as plainly indicated in Figs. 1 and 4. The triangular members 22 alternate with similar members 23 of a ring-shaped sparking member 24 having a hub 25 fitting into the inner end of the bore 13 and abutting against the inner end of the core 17, as plainly shown in Fig. 2. A washer 26 is interposed between the ring-shaped member 24 and the inner end of the body 10. It will be noticed that the triangular members 22 and 23 are spaced apart and are arranged in alternate relation with the opposite sides of adjacent members 22 and 23 approximately parallel to provide a spark gap between adjacent members. By turning the disk 21 its members 22 can be moved nearer to or farther from the corresponding members 23 of the ring-shaped member 24 to correspondingly decrease or increase the spark gaps.

In order to properly insulate the sparking members 22 and 23 from each other, the following arrangement is made: A tubular insulating material 30, preferably of cylindrical layers of mica, fits on the inner end portion of the conductor 19 and rests at its inner end on the disk 21 while the outer portion fits into a counterbore 31 formed cen-

trally in the core 17. A washer 32 of asbestos or similar material rests on the disk 21 and on this washer 32 rests a ring 33 of porcelain, and on the outer face of this ring 5 rests a washer 34 of asbestos. The washer 34 abuts against the inner face of the ring-shaped sparking member 24. The washers 32, 34 and the ring 33 are overlaid at their peripheral faces by the corresponding 10 sparking members 22 and 23 to properly insulate the same from each other and at the same time prevent adherence of carbon deposits and other extraneous matter. The spark plug is usually used with its axis in a vertical position, and soot or other extraneous matter is not liable to adhere to the sparking members 22, 23 owing to their inclined sides and such matter cannot lodge under the said sparking members as they fit snugly 15 onto the peripheral face of the insulation formed of the washers 32, 34 and the ring 33. By providing the metallic washer 26 and engaging the hub 25 of the sparking ring 34 with the body 10, a very good electrical connection is had with the body 10 to insure proper sparking.

In order to securely hold the sparking members in position on the inner end of the body 10 and to allow of adjusting the 20 sparking members 22 relative to the sparking members 23, the following arrangement is made: The conductor 19 is engaged by a fiber washer 40 resting on the outer end of the core 17, and on this washer abuts a 25 spring washer 41 against which screws a nut 42 screwing on the outer end of the conductor 19, thus on screwing up the nut 42 the head 20 draws the disk 21 and the insulation formed of the washers 32, 34 and the 30 ring 33 against a ring-shaped sparking member 34 whereby the washer 26 is pressed firmly against the inner face of the body 10. When it is desired to adjust the sparking members 22 nearer to or farther from the 35 sparking members 23, it is only necessary for the operator to partly unscrew the nut 42 to allow of turning the disk 21 with a view to move the sparking members 22 nearer to or farther from the sparking members 23. After the desired adjustment is 40 made the nut 42 is screwed up to securely fasten the several parts in position on the body 10, as above explained. On the outer threaded end of the conductor 19 screws the 45 usual clamping nut 43 for clamping the end of the circuit wire in position on the nut 42.

In the modified form shown in Fig. 5, the core 50 for the rod conductor 51 is formed of layers of mica of which the innermost layer rests on the disk 21 and the outermost is engaged by the washer 40 (not shown), otherwise the construction relative to the sparking device is the same as above described relative to Figs. 1 and 2.

In the modified form shown in Fig. 6, the 65 disk 60 is provided with sparking members 61 similar to the sparking members 22, and the sparking members 61 operate in conjunction with sparking members 62 similar to the 70 sparking members 23 but formed integrally on the inner end of the body 10. The sparking members 61 and 62 fit onto the peripheral surface of an insulation 63 formed of layers of mica. On the inner end of the conductor rod 64 of this spark plug 75 is held a dished deflector 65 to deflect oil and other extraneous matter from the 80 sparking members 61 and 62. The core 66 is similar to the core 17 and likewise the means for fastening the parts together and securing the circuit wire in place so that further description of the same is not deemed necessary.

In the modified form shown in Figs. 7 and 8, the disk 70 has its sparking members 71 in the plane of the disk instead of being upturned, as previously explained, but the 85 sparking members 70 operate in conjunction with the sparking members 72 similar to the 90 sparking members 23 to provide the desired 95 sparking gap between the members 71 and 72. The disk 70 rests on the head 73 of the conductor rod 19 while the ring-shaped member 74 carrying the sparking members 72 rests against the washer 75 abutting 100 against the inner end of the body 10, the same as above described in reference to Figs. 1 and 2. The sparking members 72 overlie the peripheral face of an insulation 105 resting on the disk 70.

Having thus described my invention, I claim as new and desire to secure by Letters Patent:—

1. In a spark plug, two conductors, of which one is ring shaped and the other is 105 in the form of a disk, each of said conductors having spaced triangular sparking members of which the sparking members of the ring shaped conductor extend parallel to its axis, and the sparking members of the 110 said disk extend from the peripheral edge thereof, the said sparking members of the two conductors being arranged alternately, and a cylindrical insulating block disposed and completely filling the space within the 115 said ring shaped conductor and projecting therebeyond into engagement with the disk, whereby to hold the said conductors in space relation by direct engagement with both thereof.

2. A spark plug, comprising a body, an insulating core mounted within the said body and provided with a central opening, a rod conductor extending through the said opening, a disk mounted on the inner end 125 of the said conductor and provided with sparking members of triangular shape, a ring-shaped member fitting onto the inner

end of the said body and provided with
sparking members of triangular shape and
extending between the sparking members of
the said disk, and a ring of insulating ma-
5 terial mounted at its center on the said rod
conductor, said insulating ring having one
face resting on the said disk and fitting into

the said ring-shaped member, said ring-
shaped member having an inner shouldered
portion engaging the opposite face of the 10
insulating ring whereby the latter acts di-
rectly against portions of said conductors to
hold the two conductors in spaced relation.
